UNITED STATES PATENT OFFICE.

JOHN M. SELLERS, OF CHICAGO, ILLINOIS, ASSIGNOR TO SELLERS MANUFACTURING COMPANY, OF CHICAGO, ILLINOIS, A CORPORATION OF ILLINOIS.

TIE-PLATE.

No. 809,987.

Specification of Letters Patent.

Patented Jan. 16, 1906.

Application filed May 18, 1905. Serial No. 260,938.

To all whom it may concern:

Be it known that I, JOHN M. SELLERS, a citizen of the United States, residing at Chicago, in the county of Cook and State of Illinois, have invented certain new and useful Improvements in Tie-Plates, of which the following is a specification.

My invention relates to improvements in railroad tie-plates, and has for its object the furnishing of a tie-plate so constructed as that the undulations of the rails under pressure will only serve to seat the plate more securely on the tie.

A further object is to provide such a plate which is adapted for use on curves.

These and such other objects as may hereinafter appear are attained by my invention, an embodiment of which is illustrated in the accompanying drawings, in which—

Figure 1 is a perspective view of my tie-plate. Fig. 2 is a sectional view on the line 2 2 of Fig. 1 looking in the direction indicated by the arrows. Fig. 3 is a sectional view on the line 3 3 of Fig. 1 looking in the direction indicated by the arrows. Fig. 4 is a cross-section of a rail and tie-plate in position in the track. Fig. 5 is a cross-section of a modification; and Fig. 6 is a side-elevation of a railroad-track, showing tie-plates in position.

Like letters of reference indicate the same parts in the several figures of the drawings.

Referring by letter to the accompanying drawings, A indicates a tie-plate having two converging faces a' a, meeting, preferably, in the center of the plate on the line B B. C indicates a flange, and D D the bolt-holes. The faces of the plate may also slope downwardly and inwardly from the flange, as shown in Fig. 3, and the plate is of a greater thickness at the flange E than at the end E'.

In Fig. 5, A' indicates a modified form of my plate, in which the plate is crowned, but not tapered transversely.

With the tie-plates now in use the undulations of the rails caused by the passage of trains rock the plates and cause them to cut into the tie, thereby admitting moisture and breaking the protected surface of creosoted ties, besides furnishing an unstable rest for the rails and tending to work the spikes loose. Referring to Fig. 6, F F indicate cross-ties, upon which rest a section of rail G, and a portion of a wheel is shown at H. When the

wheel is directly over my improved tie-plate, the pressure is a downward thrust exerted entirely at B, which, being in the center of the plate, serves to more firmly hold the plate in place without motion of any kind. When the wheel reaches the position indicated in dotted lines, the slight bend or undulation of the rail (indicated in dotted lines) brings the bottom of the rail against the faces a' a of adjacent plates, thus exerting a downward thrust that is distributed over the entire surface of one face of each plate. At no time during the passing of a load over the rails is the pressure exerted merely at one point outside the center of the plates.

The use of my improved crowned plate prolongs the life of the rail, as well as effecting a great saving in track maintenance, doing away, as it does, with the incessant pounding of the plate on the tie and the consequent loosening of the tie in the ballast.

While I have illustrated two embodiments of my invention, other forms are possible without departing from the spirit thereof.

I claim—

1. A tie-plate formed with a crown extending transversely of the rail, bearing-faces sloping in opposite directions from said crown to opposite edges of the plate, and a continuous rail-retaining flange extending transversely of said crown and provided with a continuous vertical face adapted to engage the edge of a rail-flange to prevent lateral displacement of the rail.

2. A tie-plate formed with a crown extending transversely of the rail, bearing-faces sloping in opposite directions from said crown to opposite edges of the plate, and a continuous rail-retaining flange extending transversely of said crown and provided with a continuous vertical face adapted to engage the edge of a rail-flange to prevent lateral displacement of the rail, said plate being provided with a spike-hole extending through said flange on said plate and arranged to receive a spike which will be thereby so located as to co-operate with said flange in retaining a rail in position.

JOHN M. SELLERS.
